UNITED STATES PATENT OFFICE.

HENRY A. HAYDEN, OF JERSEY CITY, NEW JERSEY.

WAIST-BELT.

SPECIFICATION forming part of Letters Patent No. 447,877, dated March 10, 1891.

Application filed December 6, 1890. Serial No. 373,838. (No model.)

To all whom it may concern:

Be it known that I, HENRY A. HAYDEN, a citizen of the United States, and a resident of Jersey City, in the county of Hudson and State of New Jersey, have invented certain Improvements in Waist-Belt Attachments, of which the following is a specification.

My invention relates to devices for use on waistbelts, the main object being to prevent the waistband of the trousers from slipping below the belt. It is well understood by those who wear belts in lieu of suspenders that the trousers are apt to work down until the waistband escapes from under the belt and an unsightly gap is left between them.

My invention has for its main purpose an attachment to the belt to prevent this and to cause the belt to hold the trousers up in their proper place, all as will be more particularly hereinafter described.

In carrying out my invention I provide an elongated flattened loop to form a slide on the belt. This slide may be moved along the belt lengthwise thereof to suit the convenience of the wearer. On this slide is mounted detachably a button-grip with a pocket to take under a button on the waistband of the trousers, and thus hold the latter suspended from the belt. The button-grip is adapted to be adjusted up or down along the slide—*i. e.*, transversely of the belt—and by this means the trousers may be adjusted up or down the same as with the ordinary suspenders.

There are other minor features and advantages connected with my belt attachment which will be set forth herein.

In the accompanying drawings I have shown my belt attachment constructed in the best form with which I am acquainted.

Figure 1 shows the inside face of portions of a waist-belt furnished with one of my attachments. There may be as many of these attachments on the belt as there are buttons on the waistband of the trousers; but as they will be all alike only one is here shown. Fig.

2 is an edge view of the attachment. Fig. 3 shows a face and edge view of the slide only detached; and Fig. 3^a is a face view of a slide, illustrating some minor modifications therein.

Figs. 4, 5, and 6 are views of the button-grip, the first two being face views and the latter

a vertical section. Fig. 7 illustrates a slightly-modified form of the button-grip.

x is the belt, and *x'* *x²* are the elements of the clasp at the respective ends of the belt. 55 These elements, which may be of any kind, form no part of my present invention.

a is the slide, which is in the form of an elongated hoop or endless band, made to embrace the belt neatly. The side or bar of the 60 slide on the inner face of the belt—*i. e.*, the face next the waistband of the trousers—is provided with notches *a'* in its edge, of which there may be any convenient number. Four are shown in the drawings. 65

b is the button-grip, which is detachably secured to the inner bar of the slide. This grip may be of any convenient form; but, as herein shown, it comprises a plate bent upon itself to form a button-pocket, one of the branches 70 having a fork *b'* formed in it to receive the neck or attaching-threads of the button on the trousers. From the other branch, which forms the back plate of the grip, an attaching-clip is formed by punching out two spring 75 branches *b²*. This construction is clearly shown in Figs. 2 and 6.

The button-grip *b* is attached to the slide *a* by presenting it to one of the notches *a'* in the latter in such a position that the branches 80 *b²* will take under the metal at the margins of said notch and then forcing it into said notch. When the belt is put on, the several slides are moved and set to correspond with the buttons on the waistband, and the grips *b* 85 are hooked under respective buttons. The position of the button in the grip is seen in Fig. 2, where it is represented in dotted lines. If the trousers are too long, the grips *b* may be set in higher notches *a'* in the respective 90 slides *a*. Thus the slides *a* provide the necessary adjustment along the belt to adapt the grips to the respective buttons and the series of notches in the inner bar of the slide provides for the adjustment of the grip up or 95 down transversely of the belt.

I contemplate utilizing the slide *a* also as a slide for adjusting the length of the belt, and to this end I provide it, by preference, with a bar *a²*, (see Figs. 1 and 3,) to which the reversed end of the belt is secured. The slide may have the notches *a'* therein formed as

shown in Fig. 3—that is, they may be made widest at their inner ends. When constructed in this way, the clip on the button-grip enters the widest part of the notch and is drawn 5 down by the weight of the trousers. This renders the grip less liable to accidental detachment than when the notches are formed as in Fig. 3.

Fig. 7 illustrates a slight modification in the 10 form of the back plate of the grip *b*, in which the material above the upper spring branch of the clip is removed. This construction does not alter the operation of the device, but lessens somewhat the amount of material employed. 15

When a belt is provided with my suspending attachments, it will not be necessary to detach the grips from the trousers when they are taken off. It will suffice to unclasp the 20 belt and leave it attached to the trousers.

As shown in Figs. 1, 2, and 3, the slide *a* is 25 constructed of a single strip of sheet metal cut out with a die, bent into form, and the overlapping extremity *a*³ of the narrower outer bar compressed into a recess in the extremity of the broader bar. This construction avoids the cost of soldering or riveting and is preferred, but it is not essential.

The attachment of the end of the belt to 30 the slide is not essential, and the slide illustrated in Fig. 3^a is not provided with a slot and bar for this purpose. In any case only one of the slides used would require to be so provided.

Having thus described my invention, I 35 claim—

1. The combination, with a waist-belt, of an elongated hoop-like slide *a*, which embraces the belt and is adapted to be shifted along the same, the inner bar of said slide, which extends transversely of the belt, being provided with a series of notches *a'*, substantially as set forth. 40

2. An attachment for a waist-belt, consisting of an elongated hoop-like slide on and 45 embracing the belt, said slide having a series of securing devices on its inner bar to receive a button-grip, and a detachable button-grip, also provided with a securing device to engage those on the slide, whereby said grip 50 may be secured to the bar at different points, substantially as set forth.

3. An attachment for a waist-belt, consisting of an elongated hoop-like slide *a*, having 55 notches *a'* in its inner bar, and a button-grip *b*, having a clip composed of spring branches *b*², adapted to engage the margins of the notches *a'* in the bar, substantially as set forth.

In witness whereof I have hereunto signed 60 my name in the presence of two subscribing witnesses.

HENRY A. HAYDEN.
